Primary Examiner — Cynthia Underwood*(74) Attorney, Agent, or Firm* — Haugen Law Firm PLLC(57) **CLAIM**

The ornamental design for a phone mount, as shown and described.

DESCRIPTION

FIG. 1 is a front, left, perspective view of the phone mount of the present invention shown in FIG. 2 and showing a phone attached thereto;

FIG. 2 is a front, left, perspective view of the phone mount of the present invention;

FIG. 3 is a bottom, plan view of the phone mount shown in FIG. 2;

FIG. 4 is a top, plan view of the phone mount shown in FIG. 2;

FIG. 5 is a left elevational view of the phone mount shown in FIG. 2;

FIG. 6 is a right elevational view of the phone mount shown in FIG. 2;

FIG. 7 is a front elevational view of the phone mount shown in FIG. 2; and,

FIG. 8 is a back elevational view of the phone mount shown in FIG. 2.

The broken lines depict an environment of use wherein a phone is inserted in the phone mount of the present invention and the depiction of the phone forms no part of the claim. All other broken lines represent portions of the invention that form no part of the claim.

1 Claim, 8 Drawing Sheets(56)
